(57) **CLAIM**

The ornamental design for a handle for surgical and dental tool, as shown and described.

DESCRIPTION

FIG. 1 is a perspective view of a two-sided handle for surgical and dental tools, depicted with a tool at each end, shown in broken lines to indicate the tools form no part of the claimed design.

FIG. 2 is a perspective view of FIG. 1 with the instruments removed;

FIG. 3 is a front view of the handle of FIG. 1 (rear view mirrored);

FIG. 4 is an enlarged portion of a region of FIG. 3;

FIG. 5 is a top view of the handle of FIG. 1;

FIG. 6 is an enlarged portion of a region of FIG. 5;

FIG. 7 is a left side end view of the handle of FIG. 1 (right side end view the same);

FIG. 8 is a bottom view of the handle of FIG. 1; and,

FIG. 9 is an enlarged portion of a region of FIG. 8.

1 Claim, 5 Drawing Sheets
